[57] CLAIM

The ornamental design for an electrical receptacle, as shown and described.

DESCRIPTION

FIG. 1 is a top, front and left side perspective view of the electrical receptacle showing our new design;
FIG. 2 is a front elevational view thereof;
FIG. 3 is a right side elevational view thereof;
FIG. 4 is a top plan view thereof;
FIG. 5 is a rear elevational view thereof;
FIG. 6 is a bottom plan view thereof;
FIG. 7 is a perspective view of the electrical receptacle showing an alternate embodiment of our new design, all sides not shown being identical to those shown in FIGS. 3-6.

FIG. 1

FIG. 2

FIG. 3

FIG. 4

FIG. 5

FIG. 6

FIG. 7
